FLEXIBLE BALL PROJECTOR TOY OR SIMILAR ARTICLE

Walter F. Hayne, P.O. Box 4688,
Oakland, Calif. 94597

Filed June 12, 1970, Ser. No. 23,455

Term of patent 14 years

Int. Cl. D21—01

U.S. Cl. D34—15

Fig. 3

Fig. 4

Fig. 1

Fig. 2

FIG. 1 is a back plan view of a flexible ball projector toy or similar article constructed in accordance with my novel ornamental design;

FIG. 2 is a side elevational view thereof taken along plane 2—2 of FIG. 1;

FIG. 3 is a front plan view thereof, taken along plane 3—3 of FIG. 2;

FIG. 4 is an end elevational view thereof, taken along plane 4—4 of FIG. 2.

I claim:

The ornamental design for a flexible ball projector toy or similar article, as shown.
